UNITED STATES PATENT OFFICE.

MAX ALVINUS BUCH, OF BIRMINGHAM, ENGLAND, ASSIGNEE TO HENRY E. EDWARDS,
OF JACKSON, MICHIGAN.

VEHICLE-TOP.

1,260,960.

Specification of Letters Patent. Patented Mar. 26, 1918.

Application filed February 19, 1915. Serial No. 9,342.

To all whom it may concern:

Be it known that I, MAX ALVINUS BUCH, a subject of the Emperor of Germany, residing at Sparkbrook, Birmingham, county 5 of Warwick, England, have invented a certain new and useful Improvement in Vehicle-Tops, and declare the following to be a full, clear, and exact description of the same, such as will enable others skilled in 10 the art to which it pertains to make and use the same, reference being had to the accompanying drawings, which form a part of this specification.

This invention relates to vehicle tops and 15 is directed to a bow structure to hold the deck and a deck adapted to be secured to the bow structure.

A feature of this invention is the provision of a removable deck, that is to say, 20 the weather excluding fabric or deck is so constructed with reference to the bows that the deck may be removed, or adjusted to place, very quickly if desired, either by a repair man or by the owner of the car himself. This removable deck makes it possible 25 to manufacture the deck itself as a separate article which may be shipped to the automobile owner who may very easily place the deck on the bow structure without the aid of skilled labor.

It is desirable to manufacture the bows and assemble the same into the frame or bow structure in large quantities for receiving the deck and it is necessary therefore that 30 each frame shall have the same form and proportion, in order that the deck may be adjusted thereto under the conditions specified and when so adjusted shall lie smooth and symmetrical. By making the tubing of 35 D-form in cross section with the flat surfaces toward the inside the tubes resist distortion either by bending or twisting and the flat surfaces afford a surface to work from and a definite surface for receiving the pieces 40 constituting a joint so that the said pieces shall be and remain in one plane and not act to distort the frame. As hitherto constructed the insertion of the wood filling and the adjustment of the joint pieces has 45 necessarily more or less distorted the frame in that no two frames have the same form and proportion and therefore it was impracticable to provide a cover of a set pattern to be adjusted to the frames under the con- 50 ditions required.

The D cross section of the tubing makes possible a more compact construction with less space between the sides of the body and the uprights of the bows.

In the drawings,—

Fig. 1 is a plan view, a portion of the deck being broken away to show the bows thereunder.

Fig. 2 is a side view of my improved top.

Fig. 3 is a detailed section of the top adjacent the rear bow.

Fig. 4 is a detailed section of the top adjacent the middle bow.

Fig. 5 is a detailed section of the top adjacent the horizontal front bow.

Fig. 6 is an elevation of a complete bow.

Fig. 7 is a section of the bow taken on the line A A of Fig. 6.

Fig. 8 is a perspective of the border or stiffening strip used in the deck.

Fig. 9 is a detailed section through the front bow portion of the deck and one of the modified forms of fastening devices.

Fig. 10 is a section in detail of another modified form of fastening device.

Fig. 11 shows a still further modified form of fastening device.

The portion of the vehicle body shown is indicated as a. The deck of the top is designated b and the bow structure c. The bow structure is arranged in the now familiar one-man top style, although as far as my invention is concerned it could be used with the old or new form of top.

In Fig. 6 a complete bow is shown. It will be apparent from Figs. 6 and 7 that this bow is a single piece of metallic tubing substantially D shaped in cross section with its flat portion toward the inside and which is bent to bow form. This forms a stronger bow to resist both bending and twisting forces than the old style wooden bow with the bow socket, and also forms a cheaper bow. The old bow socket construction with the wooden core and attached joint pieces introduced a great many troubles, an important one of which was that no two assembled frames were of exactly the same shape and proportions. In my form of construction with the all metal bow with D shaped cross section, no difficulty is experienced on account of the presence or want of presence of the wooden core and the joints do not distort the assembled frame.

The deck is preferably constructed of two

pieces of weather excluding fabric, the top piece and the back piece, the two being united by overlapping adjacent the rear bow as shown in Fig. 3. This overlapping forms 5 a long pocket in which is located a stiffening strip *d* shown in full in Fig. 8. At the front of the deck the fabric is double-backed upon itself and secured so as to form another pocket which is part of the deck structure 10 and removable therewith and which contains the stiffening strip *d* which is of practically the same construction as the rear stiffening strip. The deck is fastened to the bow structure by fitting the same over the 15 studs *e* which protrude from the rear bow and the front bow. These studs are shown in Figs. 3, 5, 9 and 11. Preferably I use such a form of stud as shown in Figs. 3 and 5. In the preferred form, the tubing 20 of the rear and front bows is perforated and screw-threads tapped therein to allow the fixing of the threaded studs *e* in place. The stiffening strips are also perforated as well as the pockets of the fabric. Consequently 25 the deck may be easily fitted over the bow structure by threading the perforations of the deck over the studs. When this has been done, the cap nuts *f* may be run on the ends of the studs to hold the deck to the bows. 30 Stay straps *h* are shown running diagonally across the bow structure. This showing appears in Fig. 1. Straps *g* are fastened to these stay straps, and engage about 35 the bows as shown in Fig. 4. These straps prevent the bows from opening out beyond the desired position.

The fastening device shown in Fig. 10 requires the insertion of a screw through the deck from the outside into a screw-threaded nut in the tube. The fastening device shown in Fig. 9 requires the insertion of screws from the inside and the running of a cap nut *f* on the outside end of the screw. 40

What I claim is:

1. In a folding vehicle top a pair of metal terminal bows, a flexible deck or covering complete in itself having at its front and rear extremities pockets or loops, clamping strips located in said loops and completely encircled thereby, and means detachably securing said clamping strips to the said terminal bows. 50
2. In a vehicle top, the combination of a bow structure, a removable deck provided with pockets at the front and rear, a stiffening strip having perforations fitting into said pockets, and threaded studs for passing through the perforations in the deck and 60 stiffening strips and for securing the same to the front and rear bow structure. 65
3. A top having an all-metal curved bow formed of a single piece of sheet metal tubing having a convex outer surface and a flat inner surface extending substantially the full width of the tubing.

In testimony whereof I sign this specification in the presence of two witnesses.

MAX ALVINUS BUCH.
